MARINE DRILLING RIG

Homer J. Woolslayer, Erwin A. Campbell, and
Cecil Jenkins, Tulsa, Okla., assignors, by mesne
assignments, to Lee C. Moore Corporation,
Pittsburgh, Pa., a corporation of Pennsylvania

Application October 31, 1945, Serial No. 625,750

4 Claims. (Cl. 114—0.5)

1

This invention relates to oil well drilling apparatus, and more particularly to apparatus for drilling wells under bodies of water.

In some localities oil is found under bodies of water, such as bays, lakes or oceans. One way of drilling for this oil is to construct an oil well derrick in the usual manner on piling driven into the bed of the body of water at the desired location. Drilling has also been accomplished by means of ordinary derricks mounted on barges of special design that are floated out to the well site and then sunk onto piles or onto bottom, depending upon the depth of the water. Among the difficulties attendant upon this procedure is the danger of the barge capsizing while carrying a tall derrick, especially when the water is rough or when strong winds are blowing. To guard against this the barge must be very wide, thereby increasing the cost of the equipment.

It is among the objects of this invention to provide a method and apparatus for drilling oil wells under water which are safer, more economical, and more easily handled than heretofore.

In accordance with this invention a substructure for a well drilling derrick or mast is mounted on a barge. Extending from the top of the substructure toward the rear end of the barge is a mast which, when not in use, is in a reclining position. In that position the mast legs are located at its top and bottom, and the mast extends only a short distance above the barge. There are means on the back portion of the substructure to which the lower legs of the mast are hinged, and means at the rear end of the barge for supporting the reclining mast substantially horizontal above the barge. A hoist drum, driven by an engine, is mounted on the substructure for swinging the mast forward relative to the barge and upward to upright position. When the mast reaches upright position the lower ends of its upper legs, which then are upright, are detachably connected to the substructure to hold the mast upright. The mast is raised by a line passing from the drum up over a gin pole mounted on the substructure in front of the mast. With this structure the barge can be floated to the desired location with the mast lowered.

In one form of the invention the substructure is skidded off the barge onto piles driven around the well. The mast can be raised either before or after the skidding operation. In another form of the invention the mast is mounted permanently on the barge, so the front end of the barge and the mast's substructure are provided with a long slot to permit the barge to be backed away from

2

the well casing extending up through it. When the barge is in the correct location it is sunk onto a suitable support, and then the mast is swung up into upright position above the well. In this embodiment the engine for the draw-works preferably is mounted on the barge beneath the reclining mast.

The invention is illustrated in the accompanying drawings in which Fig. 1 is a plan view of our 10 mast lying on a barge; Fig. 2 is a side view thereof but also indicating in broken lines the upright operative position of the mast; Fig. 3 is a view similar to Fig. 1 of another embodiment of the invention; and Fig. 4 is a side view of the second 15 embodiment and indicating in broken lines the upright operative position of the mast resting on piling.

Referring to Figs. 1 and 2 of the drawings, a 20 barge 1 is provided at its front end with a rearwardly extending central slot 2 through which an oil well, indicated at 3 in Fig. 1, can be drilled into the ground underlying the body of water on which the barge floats. Rigidly mounted on the front end of the barge is an oil well derrick substructure 4 formed in any conventional manner, such as from structural steel elements. This substructure likewise is bifurcated so that it too can straddle the well. It extends for some distance 25 behind the slot in the barge to form a support 30 for the usual draw-works which has a housing 6 in which a cable drum 7 is rotatably mounted. This drum is driven by belts and pulleys from one or more engines 8 mounted on the barge behind the substructure.

The derrick or mast 11 is shown in lowered or 35 inoperative position in which it extends from the top of the substructure rearwardly along the barge above the engines 8. The lower legs 12 of the reclining mast are pivoted or hinged at one 40 end to opposite sides of the draw-works housing, while the opposite end of the mast is supported above the barge by a supporting member 13 mounted on the rear end of the barge. The distance that the substantially horizontal mast projects beyond the back of the barge depends on 45 the length of the barge and the length or height of the mast. The upper legs 14 of the reclining mast are jointed at points 16 above the engines to provide hinged sections 17 that extend toward 50 the draw-works. Diagonal braces 18 connect the pivoted ends of the lower legs to the upper legs at their joints 16. The upper side of the mast is open for at least most of its length.

Extending above substructure 4 is an upwardly tapered gin pole that has front and rear legs

connected at their upper end by a cross member 21. The lower ends of the front legs 22 are secured to brackets 23 mounted on the front ends of the forks of the substructure, while the lower ends of the rear legs 24 of the gin pole are connected to the draw-works housing adjacent the lower legs of the mast. A cable line 26 is wound on the draw-works drum and passes upwardly over a sheave 27 at the top of the gin pole. From there the line extends rearwardly to the crown block 28 of the mast and then forward into the mast to the traveling block 29.

In order to raise the mast, the traveling block temporarily is hooked onto a sling 31 the ends of which are secured to the opposite ends of the gin pole's cross member 21. When the draw-works drum is rotated to reel in line 26, the pull of the traveling block on the sling swings the mast upwardly and forwardly into upright position. The hinged sections 17 of upper legs 14, which now are upright, then are swung forward and their lower ends detachably connected in any suitable manner to brackets 23 on the substructure in order to hold the mast upright, as indicated in broken lines in Fig. 2. This procedure is reversed when it is desired to lower the mast. In using this equipment the barge is towed out to the well site with the mast lowered in the reclining position shown in the drawings. With the mast lowered, high winds and rough water are not serious obstacles to floating the barge to the desired location. When the barge reaches the well site water is admitted to the barge to cause it to sink onto piles that previously have been driven, or, if the water is shallow enough, the barge is sunk onto bottom. The engines 8 then are operated to cause the draw-works to reel in line 26 so that the mast will be swung up into upright position as previously explained. As soon as the lower ends of the upright upper legs have been attached to substructure brackets 23, the mast is ready for use and a well 3 can be drilled down through the inner end of the slot 2 in the substructure and barge. During drilling, this slot can be floored over. After the well has been drilled, the mast can be lowered to its original reclining position and then the barge pumped out so that it will float again. The barge is then ready to be backed away from the well, which is permitted because the bifurcated end of the barge straddles the well head. It will be seen that the hazards heretofore attendant upon floating an upright mast over a body of water are avoided with this apparatus because, during travel to and from the well, the mast lies down upon the barge where it is quite seaworthy. In its lowered position the mast extends away from the bifurcated end of the barge and over the draw-works and power unit, thereby conserving space upon the barge. Also, the barge can be relatively narrow because the structure is not so top heavy as to require a wide barge to balance it.

In the modification shown in Figs. 3 and 4 a rectangular substructure 35 for a mast 36 is slidably mounted on the front end of a barge 37. The lower legs 38 of the reclining mast are hinged to brackets 39 mounted on the rear portion of the substructure, and a supporting member 41 at the rear end of the barge holds the mast substantially horizontal. The upper legs 42 of the reclining mast are shorter than the lower ones and are connected to them by diagonal bracing members 43. A tapered erection gin pole on the substructure has front and rear legs connected at their upper ends by a cross

member 44. The lower ends of the rear legs 46 are connected to brackets 39, and the lower ends of the front legs 47 of the gin pole are connected to a pair of brackets 48 also mounted on the substructure near its opposite sides. The traveling block 49 in the mast is connected by a line 51 to the crown block 52 from which the line extends forward to a sheave 53 at the top of the gin pole and then down to a draw-works drum 54 which is mounted in a housing 56 on the substructure between the front legs of the gin pole. The draw-works is operated by engines 57 of a power unit mounted on the substructure in front of the draw-works. In order to permit the mast to be raised, the traveling block is hooked onto a sling 58 which has its ends secured to the opposite ends of the gin pole cross member 44. The two sides of the sling pass under sheaves 59 mounted in the mast.

In using this rig the barge is towed out to the drilling site and anchored beside an island formed from clusters of piles 61 that previously have been driven for receiving the mast. The level of the pile caps should be slightly below the deck level of the barge, with due allowance for tidal and other variations in water level. By taking on water ballast, the deck level of the barge is dropped to correspond with the level of the pile caps, and then the entire rig is skidded off the barge and onto the piles. After the substructure has been secured to the piling foundation the mast is raised by causing drum 54 to reel in line 51 which pulls the sling further into the mast. When the mast is in upright position its diagonal bracing members 43 rest against the rear legs of the gin pole to which the mast is detachably connected to hold it upright, as indicated by broken lines in Fig. 4. After the well has been drilled the mast can be lowered and the substructure then skidded back onto the barge and floated to another location. In some cases it may be desirable to raise the mast before the substructure is skidded onto the piles.

45 This apparatus materially reduces the hazardous and expensive operation of erecting a conventional oil well derrick at a marine location, and it is much more seaworthy than a conventional derrick erected permanently on a barge.

50 According to the provisions of the patent statutes, we have explained the principle and construction of our invention and have illustrated and described what we now consider to represent its best embodiment. However, we desire to 55 have it understood that, within the scope of the appended claims, the invention may be practiced otherwise than as specifically illustrated and described.

We claim:

60 1. Marine oil well drilling equipment comprising a barge having a bifurcated front end to permit it to straddle an underwater well, a bifurcated substructure rigidly mounted on the front end of the barge and also adapted to straddle 65 said well, a reclining mast extending from the top of the substructure toward the rear end of the barge, means at the rear end of the barge for supporting the reclining mast above the barge, an engine mounted on the barge under the reclining mast with the bottom of the engine located a considerable distance below the level of the top of the substructure, said reclining mast having upper and lower legs, supporting members 70 on the back portion of the substructure to which 75 said lower legs are hinged, a hoist drum on the

substructure driven by said engine for swinging the mast upward and forward to upright position, and means for detachably connecting the lower ends of the upright upper legs to the substructure to hold the mast upright.

2. Marine oil well drilling equipment comprising a barge having a bifurcated front end to permit it to straddle an underwater well, a bifurcated substructure rigidly mounted on the front end of the barge and also adapted to straddle said well, a reclining mast extending from the top of the substructure toward the rear end of the barge, means at the rear end of the barge for supporting the reclining mast above the barge, an engine mounted on the barge under the reclining mast with the bottom of the engine located a considerable distance below the level of the top of the substructure, said reclining mast having upper and lower legs, upright members on the back portion of the substructure to which said lower legs are hinged, a tapered gin pole mounted on the substructure in front of the mast and having rear legs supported by said upright members, a hoist drum on the substructure driven by said engine, a line passing from the drum up over the gin pole and rearwardly to the mast for swinging it upward and forward to upright position with the gin pole extending up into the lower portion of the mast, and means for detachably connecting the lower ends of the upright upper legs to the substructure to hold the mast upright.

3. Marine oil well drilling equipment comprising a barge having a bifurcated front end to permit it to straddle an underwater well, a bifurcated substructure rigidly mounted on the front end of the barge and also adapted to straddle said well, a reclining mast extending from the top of the substructure toward the rear end of the barge, means at the rear end of the barge for supporting the reclining mast above the barge, an engine mounted on the barge under the reclining mast with the bottom of the engine located a considerable distance below the level of the top of the substructure, said reclining mast having upper and lower legs, draw-works mounted on the back portion of the substructure and driven by said engine, said lower legs straddling the draw-works means pivotally connecting said lower legs to the opposite sides of said draw-works, a line connect-

ing the draw-works to the mast for swinging it upward and forward to upright position, and means detachably connecting the lower ends of the upright upper legs to the substructure to hold the mast upright.

4. Marine oil well drilling equipment comprising a barge having a bifurcated front end to permit it to straddle an underwater well, a bifurcated substructure rigidly mounted on the front end of the barge and also adapted to straddle said well, a reclining mast extending from the top of the substructure toward the rear end of the barge, means at the rear end of the barge for supporting the reclining mast above the barge, an engine mounted on the barge under the reclining mast with the bottom of the engine located a considerable distance below the level of the top of the substructure, said reclining mast having upper and lower legs, draw-works mounted on the back portion of the substructure and driven by said engine, said lower legs straddling the draw-works and being pivotally connected to its opposite sides, a tapered gin pole mounted on the substructure in front of the mast and having rear legs supported by said opposite sides of the draw-works, a line for connecting the draw-works to the mast to swing it upward and forward to upright position with the gin pole extending up into the lower portion of the mast, and means for detachably connecting the lower ends of the upper legs when upright to the substructure to hold the mast upright.
